UNITED STATES PATENT OFFICE.

GEORGE STILMON JOHNSON, OF CROWLEY, LOUISIANA.

COMBINED SHAFT-SUPPORT AND ANTIRATTLER.

SPECIFICATION forming part of Letters Patent No. 686,406, dated November 12, 1901.

Application filed March 23, 1901. Serial No. 52,586. (No model.)

To all whom it may concern:

Be it known that I, GEORGE STILMON JOHNSON, a citizen of the United States, residing at Crowley, Acadia parish, and State of Louisiana, have invented a new and useful Combined Shaft-Support and Antirattler, of which the following is a specification.

The invention relates to a combined shaft-support and antirattler.

10 The object of the present invention is to provide a simple, inexpensive, and efficient device designed to be applied to shafts during their manufacture and also after the same have been in use and adapted to strengthen 15 and support the connection between the cross-bar and the shafts and to brace the curved portion of the latter and to prevent the thill-coupling from rattling.

10 The invention consists in the construction 20 and novel combination and arrangement of parts hereinafter fully described, illustrated in the accompanying drawings, and pointed out in the claims hereto appended.

25 In the drawings, Figure 1 is a perspective view of a combined shaft-support and antirattler constructed in accordance with this invention and shown applied to a portion of a shaft and a cross-bar. Fig. 2 is an enlarged sectional view, partly in elevation, illustrating 30 the arrangement of the antirattler-spring. Fig. 3 is a detail view of the transverse and a portion of the longitudinal brace.

35 Like numerals of reference designate corresponding parts in all the figures of the drawings.

1 designates a shaft connected to one end of a cross-bar 2 in the usual manner and provided at its rear end with a thill-iron 3, terminating in an eye 4, which is pivoted by a coupling-bolt 5 between a pair of forwardly-extending 40 perforated ears 6 of an axle-clip 7, and the latter is provided with a clip-plate 8, which is secured to the axle-clip by nuts 9. The foregoing parts are of the ordinary construction, 45 and the present invention comprises a longitudinal brace 9, a transverse brace 10, and an antirattler-spring 11, all constructed from a flat steel bar and formed integral with one another. The longitudinal brace 9, which is 50 inclined, extends from a point in rear of the cross-bar 2 to the rear end of the shaft, and

the transverse brace 10, which is arranged at an angle to the longitudinal brace, extends from the front end thereof to the cross-bar 2, near the adjacent end thereof.

55 The device is provided at the angle formed by the braces with an eye 12, which is secured to the lower face of the shaft by means of a bolt 13 or other suitable fastening device, and the front end of the transverse brace is 60 provided with an eye 14, which is secured to the lower face of the cross-bar by a bolt 15 or other suitable fastening device. The lower end of the longitudinal brace is connected with the lower end of the thill or shaft by a 65 bolt 16, passing through the thill or shaft, the thill-iron, and a perforation of the device, as clearly indicated in Fig. 2 of the accompanying drawings. The braces strengthen and increase the rigidity of the connection between 70 the cross-bar and the shaft and brace and strengthen the bent portion of the shaft, making the latter more rigid at this portion.

75 The metal is reduced to form the antirattler-spring, which consists of a shank 17, having a lower curved portion 18 and a vertical approximately inverted-U-shaped loop 19, which is interposed between the eye of the thill-iron and the axle-clip and which is compressed when the shafts are coupled to 80 the axle, whereby the resiliency of the spring will prevent the parts from rattling. The straight portion of the shank extends along the thill-iron, and the lower curved portion conforms to the configuration of and passes 85 around the bottom of the eye 4, and the loop 11 extends upward above the eye, as clearly shown in Fig. 2. The rear side of the loop depends below the front portion of the axle-clip and presents a slightly concave face to 90 the same.

95 It will be seen that the device is exceedingly simple and inexpensive in construction, that it is adapted to be readily applied to shafts in use as well as to those being manufactured, that it is capable of supporting and bracing the connection between the cross-bar and the shaft and the bent portion of the latter, and that it increases the rigidity of such parts and at the same time prevents 100 the thill-coupling from rattling.

What I claim is—

1. The combination with a shaft, and a cross-bar, of the combined support and anti-rattler comprising the inclined longitudinal brace extending from the lower end of the shaft to a point in rear of the cross-bar, the transverse brace extending from the front end of the longitudinal brace to the cross-bar at a point between the ends thereof, and the antirattler-spring extending around the lower end of the shaft and terminating in a loop, substantially as described.

2. The combination with a shaft, and a cross-bar, of the combined support and anti-rattler consisting of a single piece of spring metal and comprising the longitudinal and transverse braces arranged at an angle to each other and secured to the shaft and to the cross-bar, and the antirattler-spring ex-

tending from the rear end of the longitudinal brace, substantially as described.

3. The combination with a shaft, of a brace supporting the same, and an antirattler-spring formed integral with the brace and consisting of a shaft having a curved portion extending around the lower face of the eye of the thill-iron, and an inverted-U-shaped loop located in rear of the said eye and arranged to be interposed between the same and an axle-clip, substantially as described.

In testimony that I claim the foregoing as my own I have hereto affixed my signature in the presence of two witnesses.

GEORGE STILMON JOHNSON.
